UNITED STATES PATENT OFFICE.

CLARENCE E. TUCKER, OF GREAT FALLS, VIRGINIA, ASSIGNOR TO TUCKER SLICING MACHINE CORPORATION, OF WILMINGTON, DELAWARE, A CORPORATION OF DELAWARE.

SLICING-MACHINE.

1,260,479.

Specification of Letters Patent. Patented Mar. 26, 1918.

Application filed June 7, 1917. Serial No. 173,336.

To all whom it may concern:

Be it known that I, CLARENCE E. TUCKER, a citizen of the United States, residing at Great Falls, in the county of Fairfax and 5 State of Virginia, have invented certain new and useful Improvements in Slicing-Machines, of which the following is a specification.

This invention relates to improvements in 10 vegetable slicing machines and like devices, and has for one of its objects to simplify and improve the construction and increase the efficiency and utility of devices of this character.

15 Another object of the invention is to provide a simply constructed device including a reciprocating knife having coacting cutting edges and adapted to operate at both the forward and rearward stroke.

20 Another object of the invention is to provide a device of this character wherein the sliced material is prevented from being thrown from the machine by the rapid movements of the parts, means being provided to 25 permit the removal of any material which may tend to clog the machine without detaching any of the parts.

Another object of the invention is to provide a device of this character which may 30 be readily attached to a table or like support in convenient position for use, and which may be quickly detached for transportation or storage.

With these and other objects in view, the 35 invention consists in certain novel features of construction as herein shown and described and then specifically pointed out in the claim which is attached to and forms a part of this application.

40 Figure 1 is a longitudinal sectional elevation;

Fig. 2 is a plan view;

Fig. 3 is an end elevation;

45 Fig. 4 is a detached perspective view on a reduced scale of the cutting blade;

Fig. 5 is a detached perspective view on a reduced scale of the slidable knife holding member.

Corresponding and like parts are referred 50 to in the following description and indicated in all the views of the drawings by the same reference characters.

The improved device comprises a casing or support including sides 10 spaced apart, 55 and a bottom 11. The bottom 11 extends the

full length of the casing and is provided with a central relatively large opening 12, with the remainder of the bottom preferably sloping downwardly from the ends toward the opening, as illustrated in Fig. 1. 60 Formed in the confronting faces of the sides 10 are longitudinally directed guide channels 13 in which a knife supporting member 14 is arranged for movement longitudinally of the body. The member 14 is provided 65 with a relatively large opening 15 intermediate its ends and provided with a projection 16 at one end to pivotally support a connecting rod 17. The body portion including the sides 10 and bottom 11 is supported at one end by legs 18 and at the other end by legs 19. The legs 19 are coupled by a transverse web or bar 20, the bar and the lower ends of the legs 18 resting upon a support, for instance a table top, indicated 70 conventionally at 21. Depending from the legs 19 are L-shaped members 22 having threaded apertures to receive clamp bolts 23, the latter having swiveled heads 24 at one end to engage the underside of the table top 80 21 and a thumb nut 25 at the opposite end, as shown in Figs. 1 and 2. By this means the body may be clamped to the support 21.

Extending from the web 20 is an arm 26 to the outer end of which a lever arm 27 is 85 pivoted at 28. The rod 17 is pivoted at 29 to the lever 27 as shown. By this means it will be obvious that the member 14 may be reciprocated within the guide-ways 13 by actuating the lever 27. The member 26 is 90 provided with upper and lower inclined stops 30—31 to limit the movement of the lever 27 and prevent it from being moved abnormally inwardly or outwardly. By this arrangement the movable member 14 will not 95 be displaced when the lever is actuated.

Rising from the sides 10 of the support is a receptacle 32 for the vegetables to be sliced. The receptacle 32 is open at the upper and lower sides and thus communicates with the space between the sides 10. A presser block 33 is preferably arranged to move vertically within the receptacle 32, to produce the requisite pressure upon the material being sliced. Rising from the side 105 edges of the member 14 are ribs 34, the ribs being placed opposite the opening 15 and each provided with a longitudinally directed seat 35. The knife 36 is represented conventionally more particularly in Fig. 4 110

and is formed with oppositely arranged cutting edges with the terminals 37 conforming to and adapted to engage in the seats 35 in which they are secured in any suitable manner, as for instance by screws. By this arrangement the upper edges of the ribs 34 and the upper face of the cutting member operate in close proximity to the lower edges of the receptacle 32, so that as the member 14 is moved backwardly and forwardly by actuating the lever 27 the blade severs the material which projects below the lower line of the receptacle. The cutting edges of the member 36 extend obliquely to the longitudinal plane of the member 14, as illustrated in Fig. 2, so that they produce a shearing action upon the material to be severed. The channels 13 it will be noted by reference to Figs. 1 and 2, are located 20 a considerable distance below the lower line of the receptacle 32, this space gaging the thickness of the material to be sliced. At its lower edge the member 32 is formed with lateral projections 38 to increase the bearing 25 face between the member 32 and the reciprocating blade.

It will be noted that as the lever 27 is actuated the member 14, together with its cutting blade, will be moved backwardly 30 and forwardly beneath the receptacle 32, thus severing a slice of the material at each forward stroke, and another at the return stroke, the severed material falling through the opening 15 and thence through the opening 12 into a suitable receptacle disposed upon the support 21 and beneath the opening 12.

As the lever 27 is rapidly vibrated the slices of the severed material are liable to

be thrown forwardly and rearwardly of the opening 12, but by extending the bottom 11 to the ends of the casing, all the severed material will be caught by the sloping bottom 11 and conductor to the opening 12.

The casing being open at the ends, the space between the reciprocating member 14 and the reversely sloping bottom 11 is unobstructed, so that in event of the clogging of the sliced material the obstruction can be readily removed by inserting a suitable implement through the open ends of the casing.

The improved device is simple in construction, will preferably be constructed wholly of metal, and may be of any required size and is operative for slicing vegetables or various kinds of fruits, and the like.

Having thus described the invention, what is claimed as new is:

In a device of the class described, a support including side members having longitudinally directed guide channels extending in parallel relation and a bottom extending substantially the full length of the side members and having an intermediate opening, said bottom sloping toward the opening from each end, a receptacle for the vegetables to be sliced carried by said support above the opening of the bottom, a reciprocating member movably engaging in said channels and having an intermediate opening, and a cutting blade carried by said reciprocating member and supported above the opening thereof and movable closely beneath the lower edge of the receptacle.

In testimony whereof I affix my signature.
CLARENCE E. TUCKER. [L.S.]
